UNITED STATES PATENT OFFICE.

SERGIUS TIMOCHOWITSCH, OF MOSCOW, RUSSIA.

VENTILATING SYSTEM FOR ROOMS AND THE LIKE

No. 882,219.

Specification of Letters Patent. Patented March 17, 1908.

Application filed March 7, 1905. Serial No. 248,802.

To all whom it may concern:

Be it known that I, SERGIUS TIMOCHOWITSCH, a subject of the Emperor of Russia, residing at Mjasnitzkaja, No. 24, Moscow, in the Empire of Russia, engineer, have invented a certain new and useful Ventilating System for Rooms and the Like, of which the following is a specification, reference being had to the drawings hereunto annexed 10 and to the figures and reference-numerals marked thereon, that is to say—

According to the usual systems of ventilation by means of fresh or outer air which has not been previously heated, the air is introduced into the apartment through apertures which are located along the upper part of the walls or in the ceiling and sometimes provided with filtering or ventilating devices while the heated foul air passes away 20 through outlets provided in the walls near to and slightly above the floor.

The object obtained by this arrangement is to thoroughly mix the fresh air coming from the outside with the vitiated air in the room. In practice such an arrangement of inlets and outlets is attended with an undesirable draft which is most injurious in the case of invalids and, especially in large rooms, results in an irregular distribution of 30 the incoming air, and affects only the strata of vitiated air nearest to the outlets along the floor, while it has no appreciable effect upon the large volume of vitiated air in the central area of the room. It was for this 35 reason that this system of ventilation was abandoned and ventilation by means of heated air was introduced. Although, however, some of the evils attending the above described cold air system of ventilation 40 could thus be avoided yet they were replaced by other drawbacks, the chief of which is that air, previously heated contains microscopically small particles of dust and other impurities which pass through any of the 45 usual filters available for the purpose and that the air in the room ventilated by such heated air which is generally passed through dark heated tubes cannot be compared with and hygienically does not possess the same 50 value as fresh air which has not been previously heated.

Now the object of the present invention is to utilize the advantages of the two aforesaid

systems of ventilation while avoiding the disadvantages thereof. This result is attained by introducing into the apartment at or near the ceiling thereof fresh outer air which has passed through filtering devices and in extracting the foul or vitiated air from the room through outlets arranged in or near the ceiling, and preferably provided with fans.

Experiments have shown that fresh cold air has little or no affinity for foul or vitiated heated air and when the same is introduced into an apartment it has great difficulty in mixing with the foul heated air, so that a number of separate strata are formed which slide one along the other without any complete mixture resulting. By the peculiar arrangement of inlets and outlets according to the present invention this principle is to some extent utilized and the result attained is that the incoming fresh air which owing to its lower temperature and greater specific gravity falls from the ceiling toward the floor, comes into contact with the lighter ascending warmer foul or vitiated air along a comparatively extensive area or surface and consequently causes the incoming fresh air to become more or less heated without mixing to any great extent with the foul or vitiated air, while furthermore by the peculiar arrangement of inlets and outlets a draft is altogether avoided.

This invention is capable of being carried out in a variety of ways and may be applied under various conditions but the following are examples of its applications to rooms and the like.

In the accompanying drawings, Figure 1 illustrates a transverse section of a room or hall fitted with a ventilation system according to the present invention. Fig. 2 is a similar view of a room illustrating a modification in the ventilation arrangements. Fig. 3 is a similar view of a room illustrating a further slight modification.

Referring to Fig. 1, 1 represents a number of partitions or beams provided beneath the ceiling 5 of the room and each furnished for its entire length with a number of horizontal perforations or ways 2 arranged in close order. Underneath these beams 1 is fastened by suitable means a layer of filtering material 100 3 consisting of one or more sheets of wire

gauze or other suitable perforate or porous material, the points of attachment thereof to the beams 1 being covered by decorative bands or moldings 4 of any desired pattern.

- 5 Fresh air is introduced into the space between the ceiling 5 and the layer of filtering material 3 by means of a number of passages 6 which if desired may be provided with fans 7 and by reason of the perforations 2 in the 10 beams the air is enabled to circulate throughout the entire area of said space. The outlet passages for the foul or vitiated air are according to this invention provided by means of pipes 8 passing through the ceiling itself or 15 passages 9 passing through the wall of the room in immediate proximity to the ceiling.

Air extractors or fans 10 of any suitable construction and actuated in any suitable way may be provided if necessary in the 20 pipes 8 or passages 9 in order to assist the removal of the foul or vitiated air from the room.

The fresh air introduced by the various inlets 6 is distributed over the entire area of 25 the space between the ceiling 5 and the layer of filtering material 3 and passes into the room through said filtering layer 3, after the particles of dust and the like have been arrested thereby, in finely divided inappreciable streams or currents. This fresh cool air 30 entering by the ceiling descends toward the floor of the room and thus comes into fairly intimate contact with the ascending foul warm air, which also is or may be sucked up 35 by the fans 10, without becoming mixed with such foul air to any serious extent and the incoming cold air is thereby more or less heated before reaching the occupants of the room, so that the general atmosphere of the 40 room is maintained in the required fresh condition without being actually cool. Thus the danger to the occupants of the room of catching cold is avoided and, owing to the peculiar arrangement of the inlets and outlets, 45 no current of air is apparent to the occupants, even if, both in the inlets and outlets, ventilators or fans are in operation so that with the introduction of a moderate volume of air into the room the atmosphere thereof 50 can be maintained in a fresh and wholesome condition without creating any appreciable draft.

In the example given at Figs. 2 and 3 the 55 ventilation system corresponds essentially with the construction illustrated in Fig. 1, except that in this case a space covering the entire area of the ceiling is not inclosed by the ventilating and filtering layer 3 but in lieu thereof a distributing box, channel, or 60 conduit 11 of a flattened section is provided beneath the ceiling and covered on its underside with a layer of gauze or other suitable filtering material 12, and this flat distribut-

ing box or channel which extends all round or it might be across the ceiling as shown at 65 Fig. 3 is connected at one or several points with the air inlets 6. Outlets 8 and 9 are provided in the same way as hereinbefore shown and described with respect to Fig. 1 that is to say they are arranged in the ceiling 70 of the room or in the wall in close proximity to the ceiling.

It will be understood that the constructive details hereinbefore shown and described are merely given by way of example and are capable of considerable variation without departing from the spirit of the invention.

By the means hereinbefore described the foul or vitiated air is removed from a room or apartment or the like and fresh air is introduced thereinto without to any great extent mixing with the former while at the same time the incoming air is more or less heated by passing in close proximity to the outgoing warm but foul air and thus the atmosphere 85 of the room is maintained in a wholesome condition from a hygienic standpoint and by reason of the peculiar relative positions of the inlets and outlets this is achieved without creating an appreciable draft.

Having now particularly described and ascertained the nature of the said invention and in what manner the same is to be performed I declare that what I claim is:

1. In a ventilating system for rooms and the like, the combination of a chamber located directly beneath the ceiling of the room and having its under side closed by a filtering medium, air supply ways connecting said chamber with the outer air, air exhaust ways separated from said chamber and leading from the top of the room to connect the room with the outer air, and fans in said supply ways and exhaust ways.

2. In a ventilating system for rooms and the like, the combination of a chamber located directly beneath the ceiling of the room and having its under side closed by a filtering medium, air supply ways connecting said chamber with the outer air, air exhaust 110 ways passing through the walls of the room adjacent to the ceiling and air exhaust ways separated from said chamber and passing through the ceiling of the room.

3. In a ventilating system for rooms and the like, the combination of a chamber located directly beneath the ceiling of the room and having its under side closed by a filtering medium, air supply ways connecting said chamber with the outer air, and air exhaust ways passing through the walls of the room adjacent to the ceiling.

4. In a ventilating system for rooms and the like, the combination of a plurality of horizontally perforated beams extending 125 across the ceiling of the room, a covering of a

filtering medium fastened to the underside of
said beams to form a chamber directly be-
neath the ceiling, air supply ways connecting
said chamber with the outer air, and air ex-
5 haust ways separated from said chamber and
leading from the top of the room to connect
the room with the outer air.

In witness whereof I have hereunto set my
hand in the presence of two witnesses.

SERGIUS TIMOCHOWITSCH.
